DIALYZER APPARATUS

Anthony J. Carsello, Rolling Hills, Calif., assignor to
Western Gear Corporation, Lynwood, Calif., a corporation of Washington

Filed Apr. 21, 1969, Ser. No. 16,826

Term of patent 14 years

Int. Cl. D24—02

U.S. Cl. D83—1

FIGURE 1 is a perspective view of a dialyzer apparatus embodying my new design;

FIGURE 2 is a front elevational view of the dialyzer apparatus shown in FIGURE 1;

FIGURE 3 is a right side elevational view of the dialyzer apparatus shown in FIGURE 2; and

FIGURE 4 is a bottom plan view of the dialyzer apparatus shown in FIGURE 1.

I claim:

The ornamental design for a dialyzer apparatus, as shown.
